UNITED STATES PATENT OFFICE

2,525,444

SWIVELED INSULATING BUSHING

Benjamin N. Bowers, Pittsfield, Mass., assignor
to General Electric Company, a corporation of
New York

Application August 18, 1948, Serial No. 44,923

1 Claim. (Cl. 174—86)

1

This invention relates to bushings and more particularly to an adjustable cap for a multi-conductor bushing.

Normally a transformer bushing has only one electrical conductor leading from the internal apparatus to an external circuit. But in a bushing such as may be used for current transformer circuits one or more leads are used to conduct current in and out of the transformer or other apparatus. It is desired in this case that the terminal assembly or cap of the bushing (this cap normally having terminals to allow for connecting to bus bars or other apparatus) should be of such a construction that it may be rotated to any particular position with respect to the bushing proper without affecting the position of the bushing in relation to the apparatus served.

This invention accomplishes the desired result by employing two bearing members having radially projecting flanges, one bearing member being fastened to the terminal assembly and the other to the bushing or to a hollow conductor within the bushing structure. Rotatably mounted on each of these bearing members is an annular clamping ring. Means associated with the clamping rings is provided for forcing the bearing members together. The terminal assembly is first oriented in its proper position and then the annular rings are clamped together causing the bearing members to be placed in intimate contact and securely holding the bushing cap in position.

It is an object of this invention to provide a new and simple means for rotatably mounting a terminal assembly on a bushing structure.

It is a further object of this invention to incorporate in such a construction means for securely holding the terminal assembly in the prescribed position once it has been aligned.

This invention will be better understood from the following description taken in connection with the accompanying drawing and its scope will be pointed out in the appended claim.

In the drawing, Fig. 1 is a front elevation, partially in cross section of a portion of a bushing incorporating an embodiment of this invention. Fig. 2 is a plan view of the interior of a terminal assembly which may be associated with this invention. Fig. 3 is an enlarged cross sectional view of a portion of Fig. 1.

Referring now to the drawing, there is shown therein, by way of example, a portion of a transformer bushing 1 of standard construction having an outer insulating shell 2, a centrally located

2

hollow conductor 3 and concentric cylindrical insulators 4 mounted within the shell 2 and surrounding the conductor 3. Mounted above the shell 2 is a bushing dome 5 which serves as an expansion chamber for dielectric fluid contained within the shell 2. A cover 6 is placed over the dome 5 and separating the cover 6 from the dome 5 is a compression spring assembly 7 which, having been displaced or compressed at the time of the assembling of the bushing 1, serves to maintain sufficient central clamping force on the structural elements of the bushing 1 to hold it rigidly together under operating conditions. Passing through the hollow conductor 3 is a cable 8 containing, in the illustrated case, three conductors which are fastened to the terminal posts 9, 10, and 11 housed within the terminal assembly or cap 12 which is mounted above the bushing cover 6. Extending from the cap 12 and providing the means for making external connections are two terminal studs 13 and 14.

It can be seen that it may be necessary or desirable, depending upon the location of the external circuit, to orient the terminal studs 13 and 14, and thus the bushing cap 12, in a particular position. To allow the terminal assembly 12 to be oriented in any prescribed position a bearing member 15 is attached, as can be seen most clearly in Fig. 3, to the upper extremity of the bushing cover 6. A second bearing member 16 is securely fastened to the bushing cap 12. The bearing members 15 and 16, which are substantially hollow cylinders, having flanged edges which are in contact with one another. Mounted on the flanged edge of each of the bearing members are annular clamping rings 17 and 18, which may be fastened together by a plurality of bolts 19. The clamping rings 17 and 18 are free to rotate about the edges of the bearing members 15 and 16. It can be seen from the drawing that after the bushing cap 12 has been placed in its prescribed position the bolts 19 which fasten the two clamping rings 17 and 18 together may be tightened and placed under tension thus compressing a gasket 20 and forcing the electrical contact surfaces of the bearing members 15 and 16 to be placed in firm, intimate contact, locking the bushing cap 12 in place. In Fig. 2 the terminal studs 13 and 14 are shown in one possible position of the cap 12 by their dotted outline and are also shown in a position corresponding to that in Fig. 1 by the solid lines. If the bolts 19 are removed and the cable 8 is disconnected from the terminals 9, 10 and 11 the cap

12 may be removed from the bushing cover 6.

The cylindrical conductor 3 which is one of the four current-carrying leads (the other three comprising the cable 8) is electrically connected to the terminal post 21 through the bearing members 15 and 16 and the bushing cap 12.

It may be seen in Fig. 2 that terminals 10 and 11 are shunted together as are terminals 9 and 21 thus presenting a parallel connection of coils within the electrical device (not shown). To achieve a series connection terminals 9 and 10 are conductively fastened together.

While there has been shown and described a particular embodiment of this invention it will be obvious to those skilled in the art that various changes and modifications can be made therein without departing from the invention and, therefore, it is aimed in the appended claim to cover all such changes and modifications as fall within the true spirit and scope of the invention.

What I claim as new and desire by Letters Patent of the United States is:

In an electrical connector having an insulating bushing and an electrical terminal assembly wherein the terminals of said assembly are connected to conductors passing through said bushing, an arrangement for rotatably coupling said terminal assembly to said bushing, comprising, a hollow cylindrical bearing member secured to said terminal assembly and a second hollow cylindrical bearing member secured to said bushing, said bearing members being constructed of elec-

trically conductive material, each of said bearing members having a radially projecting flange, said flanges being disposed for electrical conducting contact one with the other, an annular groove in the surface of one of said flanges which is in contact with the other flange, a resilient gasket in said groove, the walls of said groove being of unequal height so that the higher one acts as a stop for limiting the compression of said gasket, an annular clamping ring associated with each of said bearing members and adapted to engage said respective flanges, means for securing said annular clamping rings one to the other, said means placing said bearing members in compressive contact, an electrically conductive housing for said terminal assembly, said housing being conductively connected through said bearing members to one of said conductors passing through said bushing, and a plurality of insulated electrical terminals extending outwardly from said housing perpendicular to the axes of said cylindrical bearing members.

BENJAMIN N. BOWERS.
